(57) **CLAIM**

The ornamental design for a medical imaging device, as shown and described.

DESCRIPTION

FIG. 1 is a front, elevational view of the medical imaging device showing our new design;

FIG. 2 is a back elevational view thereof;

FIG. 3 is a top plan view thereof;

FIG. 4 is a right side elevational view thereof;

FIG. 5 is a left side elevational view thereof; and,

FIG. 6 is a perspective view from the front, top, right side thereof.

The broken lines in FIG. 2 are included for the purpose of illustrating portions of the medical imaging device that form no part of the claimed design.

1 Claim, 6 Drawing Sheets

FIG. 1

FIG. 2

FIG. 3

FIG. 4

FIG. 5

FIG. 6
